PATENTED JAN. 16, 1906.

E. SEITZ.
VAPOR LAMP.
APPLICATION FILED SEPT. 22, 1904.

UNITED STATES PATENT OFFICE.

EDWARD SEITZ, OF PEORIA, ILLINOIS.

VAPOR-LAMP.

No. 810,226.

Specification of Letters Patent.

Patented Jan. 16, 1906.

Application filed September 22, 1904. Serial No. 225,517.

To all whom it may concern:

Be it known that I, EDWARD SEITZ, a citizen of the United States, residing at Peoria, in the county of Peoria and State of Illinois, have invented certain new and useful Improvements in Vapor-Lamps; and I do hereby declare that the following is a full, clear, and exact description of the invention, which will enable others skilled in the art to which it appertains to make and use the same.

This invention relates to gasoline-vapor lamps.

The object of the invention is the general improvement of such lamps.

A further and important object of the invention is the provision of automatic means, in connection with the needle-valve of a vapor-lamp, by which when the light is turned off a small vapor-jet may be directed against the generator of the lamp, which in burning keeps said generator hot and ready for instant use.

A further object of the present invention is the provision of a "pilot-light" for use in starting the light at any time and also for keeping the generator constantly heated, so said lamp may be turned up at any time to burn at its full capacity after having been turned off—for instance, as during the day.

A further object of the invention is to provide simple and thoroughly-reliable means for instantly starting a vapor-lamp without the necessity of first generating the vapor.

In the accompanying drawings, forming a part of this application, Figure 1 is a side elevation of my improved lamp in part section. Fig. 2 is an elevation of a combustion-chamber, showing a valve in the top thereof. Fig. 3 is a horizontal section of a portion of the lamp, taken on line X X, Fig. 2. Fig. 4 is a top view of a flap-valve. Fig. 5 is a horizontal section of the generator and combustion-chamber on line Y Y, Fig. 1.

Many lamps used for burning gasoline-vapor are not what may be termed "self-lighting" and must always be initially heated by burning alcohol or gasoline beneath the generator, whereby vapor may be formed to start it, after which the heat from the mantle serves to constantly produce more vapor for the steady burning of the lamp. In view of the disadvantages found in such lamps I have devised the lamp shown in the drawings, in which A indicates the usual bracket or support for the glass globe B, the same being supported in suitable manner by means

of the frame C, but a portion of which is shown. Centrally mounted in such bracket A is a vapor-combustion chamber D, depending slightly below said bracket, as at E, while above the bracket said chamber flares toward its top, where it receives a flap-valve F. (Shown in Fig. 4.) The top of said chamber D is notched at diametrically opposite sides, as at G, within which the trunnions H of the said valve F rest. At one side of the chamber D and preferably cast therewith is the generator I, consisting of leg J, with which at its lower end the gasoline-feed pipe K is connected, said pipe being either connected with an overhead tank or a tank under air-pressure, as desired. The upper end of J is closed and extends somewhat above the top of the chamber D and lies parallel with the mantle D' common to all lamps of this character. Between chamber D and the portion J just described is a pipe L, opening at its top into the said member J, as shown, its lower end carrying a cup M and also a needle-valve casting N, whose orifice is beneath the chamber D and directed to enter vapor into the latter. The stem O of the said valve carries a disk P, with which engages a fork Q, carrying a rod R, the upper extremity having pivotal connection with an arm S of the said flap-valve F, the lower end of the rod being guided in a lug N' on the valve-body, as shown. The generator I is filled with asbestos or other good filtering matter not affected by heat, through which the gasoline passes from the pipe K to the valve N, as indicated by the arrows.

In starting the lamp when first installed alcohol or gasoline is poured into the cup M and ignited. The heat therefrom vaporizes the gasoline within the generator and the valve on being opened liberates the vapor under pressure, directing it upward into the chamber D, where it is burned at the mantle, as in all lamps. The heat from the mantle serves to heat the upper extension of the generator, thereby continually forming vapor. Now when it is desired to extinguish the light the needle-valve is turned, as usual, in a direction to close it until it meets an arm T, pivoted on a lug U of a portion of the valve member N described. This prevents the entire closing of the valve and permits a very small portion of the vapor to pass up into the chamber D. With this action the disk P, by means of the fork Q, pushes the rod R upward, thereby pushing the arm S of the flap-valve upward

also to throw the valve to a horizontal position, it having hitherto occupied an upright or vertical position, as shown by full lines in Fig. 2. It will be noted that the said arm 5 S is set at an angle to the valve, so that a movement of the rod R in the direction of its length will accomplish the opening or closing movement freely, as shown by the broken and full lines in the figure last named. By 10 closing the top of the chamber D the vapor is confined, and an outlet is provided in the wall of the chamber adjacent to the generator through an aperture V, slanted upward, the vapor escaping through said aperture, having 15 been ignited from the mantle before the vapor was entirely shut off. This flame, which may be made of any size by changing the size of the aperture, serves to keep the generator heated continually, so that whenever the 20 needle-valve is opened again the lamp is in condition to burn at its fullest capacity. When the valve is opened, the valve F is brought at once to the vertical position, the mantle receiving the full head of vapor 25 ignited from the jet-flame just described. The stop member or arm T may be operated either by a spring or by gravity, it being normally in position to interrupt the movement of the needle-valve. When it is desired for any 30 reason to shut the lamp completely off, the arm is thrown out of the way, so that the plate P can approach the valve closer and permit the point of the needle to seat.

As shown in Fig. 5, the chamber D and the 35 pipe members J and L are connected integrally by the webs *a* and *b*, the heat from D being conducted through the metal webs to the entire generator members.

Other means than that shown may be employed for closing the top of the chamber D, and if the flap-valve is used other means for opening and closing it may be resorted to without departing from the spirit of my invention. Furthermore, changes may be 40 made in the various other parts of the device 45 as will suggest themselves to the experienced person.

I claim—

1. A vapor-lamp of the character described, comprising a combustion-chamber having a mantle thereon, a jet-orifice in its side and near its top, and a cut-off valve at its top, a vapor-generator alongside the combustion-chamber, a regulating-valve to control the flow of vapor from the said valve to the combustion-chamber and means connected to the vapor-generator to automatically close the top of the combustion-chamber when the valve is operated and allowing the escape of heated gases through the jet-orifice and their projection against the vapor-generator, substantially as described.

2. A vapor-lamp comprising a combustion-chamber having a mantle thereon a gasoline-vapor generator lying at the side of

said chamber and mantle, a cut-off valve in the top of the combustion-chamber, there being a jet-orifice in the side of the chamber opposite the generator for the purposes described, and means coöperating with the two valves for automatically closing the cut-off valve when the needle-valve is operated.

3. In a gasoline-vapor lamp the combustion-chamber having a mantle thereon, a vapor-generator adjacent thereto substantially as described, a valve for controlling the vapor-supply to the lamp a cut-off valve for closing the top of the chamber automatically when the controlling-valve is operated, means between the cut-off valve and controlling-valve for causing the action described, there being a jet-orifice in the side of the generator near the top for escape of heated gases against the vapor-generator when said cut-off valve is closed.

4. In a vapor-lamp, the combustion-chamber having a mantle thereon, a valve for controlling the gas admitted to such chamber, a vapor-generator adjacent to the combustion-chamber through which the gasoline must pass to reach the controlling-valve, a cut-off valve in the top of the combustion-chamber, means between the controlling-valve and the cut-off valve for closing the latter as the former is operated, there being a jet-orifice in the side of the combustion-chamber near its top and beneath the cut-off valve for allowing escape of heated gases therethrough for their projection against the vapor-generator substantially as described.

5. In a vapor-lamp, the combination of the combustion-chamber and its mantle, a vapor-generator adjacent to said chamber to which the controlling-valve of the lamp is connected, a jet-orifice in the side of the chamber near the top, a cut-off valve in the top of the combustion-chamber for inclosing the vapor therein and causing the escape of the heated gases through the said orifice and their projection against the vapor-generator, and a connection between the cut-off valve and the controlling-valve for closing the former by partially shutting the latter as and for the purposes described.

6. A vapor-lamp comprising a combustion-chamber having a mantle thereon, a combustion-chamber for the vapor, the same being positioned beside the said combustion-chamber for receiving heat from the latter and its mantle, there being a jet-orifice in the side of the combustion-chamber near its top, and a rocking cut-off valve at the top of the said combustion-chamber, operated automatically by the turning of the controlling-valve of the lamp, the said cut-off valve inclosing the heated gases and causing them to pass out through the said orifice and means between and connecting said valves for causing the action described.

7. A vapor-lamp comprising the combus-

tion-chamber D having the mantle D' thereon, the vapor-generator J, L situated close to said combustion - chamber and extending close up to and opposite the mantle as shown, 5 the needle-valve O beneath the combustion-chamber and connected with the said generator for entering vapor into said chamber, the cut-off valve F in the top of the latter member, a rod member R for rocking the said 10 valve F to open or close the chamber containing it, said rod having attachment with the valve O, the operation of the latter adapted

to operate the cut-off valve also automatically for the purposes described, there being a jet-orifice beneath the cut-off valve in the 15 side of the combustion-chamber opposite the vapor-generator as described and shown.

In testimony whereof I affix my signature in presence of two witnesses.

EDWARD SEITZ.
